UNITED STATES PATENT OFFICE.

JOSEPH EMILE ARZENS, OF PARIS, FRANCE.

SHOCK ABSORBER.

Application filed June 15, 1925, Serial No. 37,395, and in France September 9, 1924.

The object of this invention is to provide a spring-handle-bar for cycles of which the construction will be extremely simple in that it comprises very few separate parts, and to 5 which parts access can be had easily and expeditiously; the construction being very simple, thereby materially lessening the cost of manufacture.

This invention relates more particularly 10 to spring handle-bars of the type in which a part of the handle-bar having therein a split and therefore resilient collar, is contained within an encasement consisting of 15 separate parts attachable to the stem; a projecting lug, forming part of the collar, being held resiliently between two spiral springs of which one is situated above and the other below that part of the lug which projects into the stem which, as usual, is adjustably 20 fitted within the cycle-head; the arrangement being such that when the handle-bars are depressed or raised the spring on one or the other side of the lug will be compressed. In such device adjustment of the height of the 25 handles is effected by loosening a bolt which draws together two additional lugs each projecting from one side of the slit in the collar.

According to this invention, simplicity of 30 construction is attained by the integral formation of one half of the encasement with the adjustable stem of the cycle; the other and only constituent part thereof being in the form of a lid which is bolted thereto in such manner as to enable expeditious access 35 to be had to the parts within the encasement. Further simplicity of construction is attained by dispensing with additional lugs for the bolt in the collar and forming the collar of a length of material having projecting end-portions which lie one above the other and almost contiguously; said end portions having one or two clamping bolts 40 passed through them and constituting the lug which extends between the springs.

Firm retention of the handle-bar within 45 the collar is effected by pins which project from the handle-bar and respectively enter any one of two respective annularly disposed series of perforations in the collar.

For more precise description reference is 50 to be had to the accompanying drawing in which:—

Figure 1, is a view, in perspective, of a 55 spring-handle-bar constructed in accordance with my invention; Fig. 2 is a view, taken transversely of the handle-bar and in sec-

tion; Fig. 3 is a plan of the lower part of the encasement, in section.

The encasement 1 comprises a lower part 2 which is integrally formed with the upper part of the stem 4 which, as is usual, fits into the head of the bicycle frame. The part 2 comprises a socket 12 and an off-set trough-shaped portion 14. A counter-part or lid 15, having approximately the same interior shape as the part 2, is secured to the part 2 by bolts 9 and nuts 3; the side walls 17 of both parts 2 and 15 having semi-circular recesses 18 constituting openings for the passage therethrough of the handle-bar. That portion of the handle-bar which is within the casing has an enlargement 7 to prevent longitudinal movement of the handle-bar through the openings 18. This enlargement is preferably roughened on its outer surface 75 to afford a surface upon which a collar 5 will grip firmly when clamped about it.

As further security, locking of the handle-bar, to prevent any possibility of movement thereof within the collar 5, is effected by pins 10 which project from the surface of the handle-bar and respectively enter any one of two annularly disposed series of perforations 19; the adjustment of the pins into different perforations being effected by loosening the bolts 8, which permits the collar to spring open so that the perforations 19 are clear of the pins 10, raising the handles to the required height, and then tightening the bolts 8 to cause the pins to enter the required perforations. Access to the bolts 8, can be easily had by removing the nuts 3 and cover 15. The collar 5 is formed of a suitable length of flattened bar of which the end portions project beyond the collar and, lying 95 one above the other, constitute a lug 6 of which the upper and lower faces have recesses 13; the two parts of the lug being provided with bolts 8, which bind the collar about the enlargement 7 of the handle-bar.

Two spiral springs 11, each have one end within one of the sockets 12, and the other end retained in place upon the lug 6 by the recesses 13.

What I claim is:—

1. In a shock absorber for the handle-bars of cycles comprising a stem fitted adjustably into the head of a cycle, said stem having at the upper end thereof, an encasement of which one part is formed integrally with the stem and the other part thereof is attachable thereto by securing bolts.

2. In a shock absorber for the handle-bars of cycles comprising a stem fitted adjustably into the head of a cycle, said stem having at the upper end thereof, an encasement of which one part is formed integrally with the stem and the other part thereof is attachable thereto by securing bolts, and a spring retaining socket formed in each of the two parts.
3. In a shock absorber for the handle-bars of cycles comprising a stem fitted adjustably into the head of a cycle, said stem having at the upper end thereof, an encasement of which one part is formed integrally with the stem and the other part thereof is attachable thereto by securing bolts, a spring retaining socket formed in each of the two parts, a spring collar having a lug projecting from its circumferential surface, encompassing a handle-bar journalled in the encasement and having a lug formed integrally therewith and projecting from its circumferential surface, said spring-collar having annularly disposed perforations, and pins projecting outwardly from the surface of that part of the handle-bar which is within the collar.
4. In a shock absorber for the handle-bars of cycles comprising a stem fitted adjustably into the head of a cycle, said stem having at the upper end thereof an encasement of which one part is formed integrally with the stem and the other part thereof is attachable thereto by securing bolts, a spring retaining socket formed in each of the two parts, a spring collar having a lug projecting from its circumferential surface, encompassing a handle-bar which is journalled in the side walls of said casing, said collar and lug formed of a single piece of bar metal folded upon itself so that its end portions constitute the lug, a spring retaining recess formed on each of two opposite surfaces of said lug, and bolts passed through said lug.
5. In a shock absorber for the handle-bars of cycles comprising a stem fitted adjustably into the head of a cycle, said stem having, at the upper end thereof, an encasement of which one part is formed integrally with the stem and the other part thereof is attachable thereto by securing bolts, a spring retaining socket formed in each of the two parts, a spring-collar encompassing a handle-bar journalled in the encasement and having a lug formed integrally therewith and projecting from its circumferential surface, said spring-collar having annularly disposed perforations, and pins projecting outwardly from the surface of that part of the handle-bar which is within the collar.
6. In a shock-absorber for handle-bars of cycles comprising a stem fitted adjustably into the head of a cycle, said stem having, at the upper end thereof an encasement of which one part is formed integrally with the stem and the other part thereof is attachable thereto by securing bolts, a spring retaining socket formed in each of the two parts, a spring-collar encompassing a handle-bar journalled in the encasement and having a lug formed integrally therewith and projecting from its circumferential surface said spring collar having annularly disposed perforations, pins projecting outwardly from the surface of that part of the handle-bar which is within the collar and spiral springs interposed between the lug and the encasement and having their respective ends within the sockets therein and in the lug.

JOSEPH EMILE ARZENS.
